UNITED STATES PATENT OFFICE.

GEORGE K. MALTBY, OF NEW YORK, N. Y.

RUBBER HEEL.

1,159,972.

Specification of Letters Patent.

Patented Nov. 9, 1915.

Application filed May 9, 1913. Serial No. 766,526.

To all whom it may concern:

Be it known that I, GEORGE K. MALTBY, a citizen of the United States, residing in the city, county, and State of New York, have invented certain new and useful Improvements in Rubber Heels, of which the following is a full, clear, and complete disclosure.

My invention relates to rubber heels for boots and shoes of various kinds and the objects of my invention are to provide a rubber heel which, while having all of the advantages of a plain rubber heel, yet will not be liable to slip on wet or slippery surfaces, which will not be liable to damage hard wood floors and which will be strong and durable. I accomplish these objects by incorporating into the body of the rubber forming the heel a plurality of elongated preferably soft metallic strips, wires or shreds disposed at an acute angle to the lower surface of the heel and having their lower ends exposed at the lower surface of the heel. These strips, wires or shreds are preferably made of a soft metal such as lead or aluminum so that while they will prevent slipping, yet they will wear smooth at their exposed ends and remain substantially flush with the surface of the rubber. They may, however, be made of any other flexible material.

In the drawings accompanying and forming a part of this specification, I have illustrated one embodiment of my invention. In this drawing Figure 1 is a side elevation of a shoe with my improved heel attached, a portion of the heel being shown in vertical section. Fig. 2 is a bottom view of the heel and Fig. 3 is a vertical transverse section through the rubber portion of the heel taken on line 3-3 of Fig. 1.

Referring in detail to the structure illustrated, the numeral 1 designates the rubber heel, which in Fig. 1 is shown attached to the shoe 2 in any suitable manner, as by means of screws, not shown, inserted in the holes 3. Numeral 4 designates a plurality of elongated wires embedded in the rubber forming the heel and having their lower ends exposed at the bottom of the heel. The body portions of these wires are disposed at an acute angle to the top and bottom surfaces of the rubber heel so that the resiliency of the rubber will not be destroyed, as

would be the case if the wires were vertically disposed, or perpendicular to the lower surface of the heel. The wires or friction members may be made of any suitable material, such as lead, aluminum, brass, steel, etc., though they are preferably made of soft material for the reasons above stated. In the drawing these friction members are shown in the form of wires, having slight undulations therein so that the rubber will more easily adhere to them. In practice, however, they may be in the form of strips or shreds or any other shape so long as they are elongated and flexible. They may be straight and smooth though an irregular surface is more desirable. In the single embodiment which I have illustrated, these friction members are disposed throughout the body of the heel. It is to be understood, however, that in practising my invention they may be disposed only throughout the rear portion of the heel as there is more tendency for the heel to wear away or slip at this part.

While I have described only one embodiment of my invention, I am aware that other embodiments may be constructed without departing from the scope of my invention as expressed in my claims.

What I claim is:

1. A rubber heel of the kind described having a body of elastic material with a plurality of elongated friction members embedded therein, each having the entire area of its lower end exposed at the lower surface of the heel and its body disposed at an acute angle to said surface, substantially as described.

2. A rubber heel of the kind described, having a body of elastic material with a plurality of elongated friction members embedded therein arranged substantially parallel with each other, each having its lower end exposed at the lower surface of the heel, and its body inclined with respect to the lower surface of the heel, substantially as described.

3. A rubber heel of the kind described, having a body of elastic material with a plurality of elongated soft metallic friction members embedded therein arranged substantially parallel with each other, each having its lower end exposed at the lower surface of the heel, and its body inclined

with respect to the lower surface of the heel, substantially as described.

4. A rubber heel of the kind described having a body of elastic material with a plurality of elongated wires embedded therein, each having its lower end exposed at the lower surface thereof and extending to the

top surface thereof in a slanting direction from back to front.

GEORGE K. MALTBY.
